UNITED STATES PATENT OFFICE.

ALFRED G. F. KUROWSKI, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,174,076.

Specification of Letters Patent.

Patented Mar. 7, 1916.

Application filed August 6, 1913. Serial No. 783,257.

To all whom it may concern:

Be it known that I, ALFRED G. F. KUROWSKI, a citizen of the United States, residing in Brooklyn borough, city of New York, in the county of Kings and State of New York, have invented certain new and useful Improvements in Type-Writing Machines, of which the following is a specification.

10 My invention relates particularly to a device used as an attachment for the rotary platen of a typewriting machine, for holding cards and other devices, as for instance address-stencils.

15 An object of the invention is to provide a simple, practical and effective construction, permitting the card holder to be quickly attached to or removed from the platen. The card holder is in the form of a frame curved to conform to the surface of the platen. It is removably attached to supports, which are rotatably mounted, whereby the card holder may be adjusted around the surface of the platen to distribute the 20 printing area and prevent uneven wear of the platen surface, or the card holder may be removed from said supports to permit the platen to be used in the usual way. The supports for the card holder consist of rings 25 or disks journaled at the ends of the platen for adjustment about the platen axle, and held in adjusted position by pawls on said supports engaging ratchet disks fixed to the platen. The card holder is removably attached to said supports by holding devices 30 at its opposite ends, one of the supports having a latch permitting the holder to be removed. The card holder, which may extend the length of the platen, has end guides and 35 an intermediate guide forming with the platen, grooves to receive and hold the edges of the cards or work sheets which may thus be supported at either end of the platen, and the intermediate guide is preferably adjustable along the card holder frame to accommodate cards of different sizes.

40 Other features and advantages will hereinafter appear.

In the accompanying drawings which 50 illustrate a form of my invention applied to an Underwood machine of the front-strike type, Figure 1 is a perspective view of the platen with the card holder attached. Fig. 2 is a perspective view of the card holder 55 and its supports disassembled. Fig. 3 is a

fragmentary view of the right-hand end of the platen and the card holder. Fig. 4 is a part sectional end view taken at the right-hand end of the platen. Fig. 5 is a fragmentary view of parts shown in Fig. 4, 60 with the latch in released position.

The rotatable platen 1 is fixed on an axle 2 journaled in a platen frame 3. Type bars 4 are adapted to strike the front face of the platen, or a work-sheet or card for printing 65 or stenciling thereon in the usual manner. The platen can be rotated either by the usual line-space mechanism operating on the line-space ratchet wheel 5 secured to the platen axle, or the hand wheels 6 attached to the 70 ends of the axle. The card holder 7 is shown as in the form of a light frame comprising longitudinal bars 8 connected by end members or bails 9 and 10 and an intermediate member 11, said members being arc-shaped 75 or curved to conform to the surface of the platen, and resting on the platen when the holder is in position. Said parts may be formed from a single piece of sheet material, but the intermediate member 11 is preferably an additional member slidably along the holder to adjust it for cards of different lengths. Secured to or formed on said members 9, 10 and 11 are projecting flanges or guides 12 adapted to overlie the edges of a 80 card and hold it in position on the platen, said guides being spaced a short distance from the platen to provide room for the cards and having their ends 13 slightly upturned to permit the cards to be readily inserted. The guides 12 may be thin strips of sheet metal secured to the members 9, 10 and 11, and on the intermediate member 11 may be extended and have their ends 12^a upturned to engage the lower beveled edges 12^b 85 of the card holder, whereby the member 11 is slidably supported and adjustable along the holder to accommodate different sized cards.

The card holder is removably attached to 90 end supports adjustable about the platen axle to permit the card holder to be adjusted to any position around the periphery of the platen for preventing uneven wear of the platen, and in the form of the invention shown said supports consist of disks or rings 14 and 15 rotatably mounted on the ends of the platen. The ring 15 is freely mounted on the reduced end 16 of the platen, and is held thereon by a ratchet disk 17 se- 100 105 110

cured by screws 18 to the platen and formed with an annular series of ratchet teeth 19 which coöperate with a pawl or dog 20 on the ring 15 to hold the latter in adjusted position. The dog 20 may be lifted by means of a finger-piece 21 against the pressure of a spring 22 to permit the rotary adjustment of the ring. The card holder support or ring 14 at the left-hand end of the platen has a similar mounting and is held in like manner by a disk 23 secured to the platen and having ratchet teeth 24 coöperating with a spring-pressed pawl 25 pivoted on the support 14. The left-hand end of the card holder is removably attached to its support 14 by means of a hook or lug 26 fixed to the end of the holder and projecting into position to engage beneath a bail or loop 27 fixed on the holder 14, the latter having a cut-away portion 28 to accommodate the lug 26. The right-hand end of the card holder is secured to its support 15 by means of a hook or keeper 29 fixed on the under side of the frame end 10 and adapted to engage beneath a latch 30 pivoted to the support 15. The support 15 is cut away to form a pocket or recess 31 to accommodate the latch 30, its keeper 29 and a latch-holding spring 32. A pin 33 on the card-holder frame bears against a shoulder on the support 15 formed by a notch 34, and prevents accidental rotation of the card holder in either direction, said notch 34 having an inclined face to permit the holder to be readily slipped into latching position. A pin 35 projecting from the latch 30 forms a handle whereby the latch may be moved against the pressure of the spring 32 to release it from the keeper, and permit the right-hand end of the card holder to be lifted from the platen. The holder may then be slipped to the right to release the lug 26, thus removing the holder from the platen. To replace the holder, the lug 26 is placed in the loop 27 and the right-hand end of the holder then pressed down against the supporting ring 15, until the latch 30 snaps into position over its keeper 29, the ring 15, if necessary, being first rotated to bring the latch 30 opposite the keeper. The keeper 29 being seated in the pocket 31 and bearing against the vertical wall thereof, prevents endwise movement of the card holder. The card holder may be adjusted about the platen to present a fresh surface of the platen at the printing zone, by depressing the finger-pieces 21, thereby lifting the dogs 20 and 25, and then rotating the card holder with its supports 14 and 15 to any desired position relatively to the platen, the latter being held stationary during such adjustment by the usual detent engaging the line-space ratchet wheel. In the form of card holder shown, two sets

of guides 12 are provided, whereby cards or work-sheets may be supported at either end of the platen. It will be understood, however, that the form of work-holder may be widely varied within the scope of my invention.

Variations may be resorted to within the scope of the invention, and portions of the improvements may be used without others.

Having thus described my invention, I claim:

1. The combination of a cylindrical platen, supports located at opposite ends of the platen and angularly adjustable about the platen axis, means to lock the supports in adjusted position for unlimited rotation with the platen, a work-holder, and a latch for removably securing said holder to said supports.

2. The combination of a cylindrical platen, supporting members located at the ends of the platen and angularly adjustable about the platen axis, means to lock said supports to the platen for unlimited rotation therewith, and a card-holding device composed of connected members capable of being attached to or removed from said supports while the latter are locked to the platen.

3. The combination with a cylindrical platen, of a ring mounted for angular adjustment about the platen axle, a locking device to lock said ring to the platen for unlimited rotation therewith, and a work-holder composed of connected members attachable to and detachable from said ring while the latter is attached to the platen.

4. The combination with a cylindrical platen, of rings journaled at the ends of the platen, a locking dog carried by one of said rings, a ratchet secured to the platen in position to coöperate with said dog to lock said dog-carrying ring to the platen, the rings being arranged for unlimited rotation with the platen, a work-holder composed of connected members, and means for attaching said work-holder to or detaching it from said rings without disassembling the latter from the platen.

5. The combination with a cylindrical platen, of supporting rings journaled at the ends of the platen, ratchet wheels fixed to the platen, locking dogs carried by said rings to engage said ratchet wheels and hold the rings in various positions of rotative adjustment relatively to the platen, a work-holder composed of connected members, and means for attaching and detaching said work-holder to and from the supporting rings without interfering with the position of said rings relatively to the platen, said rings and work-holder when locked to the platen being arranged for unlimited rotation therewith.

6. The combination with a platen, of a card holder, a circularly adjustable support

on the platen arranged for unlimited rotation with the platen, and a latch for removably securing the holder to said support.

7. The combination with a platen, of a card holder composed of connected members, supports for said holder revolvably mounted at the ends of the platen and forming permanent adjustable attachments on the platen, and means for removably attaching the card holder to said supports.

8. The combination with a cylindrical platen and supporting members for a work-holder located at the ends of the platen and connected to rotate therewith, of means for effecting angular adjustment of said members about the platen axis to thereby adjust the work-holder over the platen surface, means for attaching one end of the work-holder to its support and releasable by an endwise movement of the work-holder, and a latch for securing the other end of the holder to its support, and preventing endwise movement of the holder, whereby the holder may be fixed to or removed from the platen by the operation of said latch.

9. The combination of a cylindrical platen, rings at the ends of the platen and adjustable angularly about the platen axle, means for holding said rings in adjusted position, a card holder, and means for removably attaching said holder to said rings, said attaching means comprising a latch to maintain said holder locked to both rings, and releasable to permit the holder to be removed from the platen and said rings.

10. A card holder frame comprising longitudinal bars, integral arc-shaped connecting members at the end of said bars, and an intermediate member adjustable longitudinally of the frame.

11. The combination of a typewriter platen, and a card holder attached to the platen to rotate therewith and extending longitudinally thereon, and comprising card-holding members curved to conform to the periphery of the platen, one of said members being adjustable toward and from the other members to accommodate cards of different sizes.

12. The combination with a cylindrical platen, of a card-holding device thereon comprising longitudinal members, end connecting members, and an intermediate connecting member, said connecting members comprising means for holding the edges of cards or work sheets, said intermediate member being adjustable toward and from the end members.

13. The combination of a cylindrical platen, a work-holder, and supports therefor by which the work-holder is attached to the platen for unlimited rotation therewith, said supports adjustable relatively to the platen, to shift the holder to any position circumferentially of the platen for dis-

tributing the printing area thereover, said work-holder being detachable from said supports without changing the relative positions of the platen and said supports.

14. The combination with a revoluble platen, of a work-holder adjustable as a whole throughout the circumference thereof to present a work-piece at different printing portions of the platen surface, revoluble supports for said work-holder on said platen, means for detachably connecting said work-holder and supports, and means for releasably securing said supports to said platen in desired positions of adjustment of the work-holder thereon.

15. The combination with a revoluble platen, of a work-holder serving a portion of the platen circumference and adjustable as a whole throughout the entire circumferential printing surface, means upon said holder adjustable to accommodate work-pieces of different widths in various longitudinal positions relatively to the platen, revoluble supports for said work-holder on said platen, and means for releasably securing said supports to said platen in desired positions of adjustment of the work-holder thereon.

16. The combination with a revoluble platen, of a work-holder serving a portion of the platen circumference and adjustable as a whole throughout the entire circumferential printing surface, means upon said holder to accommodate work-pieces of different widths in various longitudinal positions relatively to the platen, revoluble supports for said work-holder on said platen, means for detachably connecting said work-holder and supports, and means for releasably securing said supports to said platen in desired positions of adjustment of the work-holder thereon.

17. The combination of a cylindrical platen, a work-holder, supports therefor connected to rotate with the platen and adjustable angularly about the platen axis to shift the holder to any position circumferentially of the platen for distributing the printing area thereover, and means for detachably securing the work-holder to its supports to permit the work-holder to be attached to or removed from the supports while the latter are retained in their operative relation to the platen.

18. The combination of a platen, a work-holder, and supports therefor, said holder and supports being adjustable as a unit entirely about the platen circumference for distributing the printing area thereover, and said work-holder being bodily removable as a unit from its supports while the latter remain attached to the platen.

19. The combination of a cylindrical platen, supporting members mounted thereon and adjustable angularly about the

- platen axle as an axis to different positions relatively to the platen, and a card-holder attached to said supports and removable therefrom while said supports remain in any 5 position of adjustment on the platen, whereby the card-holder when replaced after removal from its supports may always be brought to the position relatively to the platen from which it was removed.
- 10 20. The combination of a rotatable platen, supports located at the ends of the platen and angularly adjustable entirely about the circumference of the platen to distribute the printing area thereover, means for holding 15 said supports in adjusted position, and an open work-holding frame removably attached to said supports and exposing within its borders a printing area of the platen surface for the work-piece, the frame comprising holding members curved around the 20 platen to engage the lateral edges of the work-piece and cause it to hug the platen.
21. The combination with a roller platen, of a card-holder, supporting members there- 25 for connected to rotate with the platen and circularly adjustable about the platen axis for adjustment of the card-holder over the platen surface, a hook to attach one end of the holder to one of said members, and a 30 latch to attach the other end of the holder to the other of said members.
22. The combination with a cylindrical platen, of a work-holder comprising a frame curved to conform to the surface of the 35 platen, annular supports over which the ends of said frame fit, a catch to removably hold the frame in one of said supports, a latch to removably hold the frame in the other of said supports, said frame and sup- 40 ports mounted to rotate with the platen, and means to adjust said supports circularly about the platen axis and thereby adjust the work-holder on the platen.
23. A card-holding attachment for a roller 45 platen comprising longitudinal parallel members with fixed arc-shaped end connecting members, and an intermediate connecting member adjustable longitudinally of the holder, said connecting members pro- 50 vided with card-holding guides arranged to form with the platen arc-shaped grooves to receive the edges of the cards, whereby said intermediate connecting member forms with either end member, a holder adjustable to 55 cards of different dimensions lengthwise of the platen.
24. The combination with a revolute platen, of a work-holding frame adjustable as a whole throughout the circumference 60 thereof to present a work-piece at different printing portions of the platen surface, said frame comprising members extending lengthwise of the platen and uniting members curved to conform to the curvature of 65 the platen surface, said uniting members

forming with the platen curved guideways to receive the lateral edges of the work-pieces, revolute supports on said platen to which said frame is releasably attached, and means for releasably securing said supports to the platen in desired positions of adjustment of the frame on the platen. 70

25. The combination with a revolute platen, of a work-holding frame serving a portion of the platen circumference and adjustable as a whole throughout the entire circumferential printing surface, said frame comprising work-holding strips curved along the platen surface and arranged to hold the lateral edges of a work-piece to thereby bow the work-piece and cause it to hug the platen, revolute supports on said platen on which the said frame is releasably mounted, and means for releasably securing said supports to said platen in desired positions of adjustment of the work-holding frame on the platen. 75 80 85

26. The combination with a revolute platen, of a work-holding frame serving a portion of the platen circumference and adjustable as a whole throughout the entire circumferential printing surface, said frame comprising members extending lengthwise of the platen and uniting members curved to conform to the curvature of the platen and forming therewith means to hold the lateral edges of a work-piece and thereby cause the latter to hug the platen, revolute supports for said work-holding frame on said platen, means for detachably connecting said frame and supports, and means for releasably securing said supports to said platen in desired positions of adjustment of the work-holding frame thereon. 90 95 100

27. The combination with a roller platen, of a card-holding frame forming an attachment therefor, said frame comprising spaced members extending lengthwise of the platen and connecting members curved to conform to the curvature of the platen, said connecting members comprising card-holding guides co-operating with the platen to form guideways for the lateral edges of work-pieces, permitting the latter to be placed on the platen while the frame is in position thereon and holding the work-pieces against the platen surface, supports for said frame at the ends of the platen and connected to rotate with the platen, and means for adjusting said supports rotatively about the platen axis to adjust the position of said frame on the platen, said frame being releasably attached to said supports for removal from and replacement on the platen while the supports are retained in their adjusted position. 105 110 115 120

28. The combination with a roller platen, of a card-holding frame forming an attachment therefor, said frame comprising spaced members extending lengthwise of the 125 130

- platen and connecting members curved to conform to the curvature of the platen, said connecting members comprising card-holding guides coöperating with the platen to 5 form guideways for the lateral edges of work-pieces, permitting the latter to be placed on the platen while the frame is in position thereon and holding the work-pieces against the platen surface, and supports at the ends of the platen arranged for 10 rotation with the platen, said supports having bearing surfaces substantially flush with the platen surface along which said connecting members bear substantially 15 throughout their length, the frame being detachably mounted on said supports for removal from the platen while the supports are retained in their connection with the platen.
- 20 29. The combination with a roller platen, of a card-holding frame comprising bars extending lengthwise of the platen, arc-shaped connecting members at the ends of said bars, supports for said frame mounted to rotate 25 with the platen and comprising arc-shaped bearing surfaces to abut said connecting members along their length, means for removably attaching said frame to said supports, and means for adjusting said supports rotatively relatively to the platen to 30 thereby adjust the frame to different portions of the platen surface.
- 30 30. The combination with a roller platen, of a card-holding frame comprising bars 35 extending lengthwise of the platen, arc-shaped connecting members at the ends of
- said bars, supports for said frame mounted to rotate with the platen and comprising arc-shaped bearing surfaces to abut said connecting members along their length, and 40 means for removably attaching said frame to said supports, said frame comprising an intermediate arc-shaped connecting member, each of said connecting members having means for holding the edges of cards 45 or work-pieces, said intermediate member being adjustable lengthwise of the frame and having its holding means arranged to coöperate with the holding means of the end members of the frame, whereby cards having different dimensions as measured lengthwise of the platen may be held between either end of the frame and the intermediate member. 50
31. The combination with a roller platen, 55 of a toothed wheel or disk at one end of the platen and connected to rotate therewith, a support mounted between the end of the platen and said disk and rotatively adjustable relatively to the platen, a locking dog 60 carried by said support to engage the teeth of said disk and thereby hold said support in its adjusted position, a support at the opposite end of the platen also mounted for rotative adjustment relatively to the platen, 65 and a card-holder releasably attached to said supports.
